INVENTOR
Constant L. Devos
BY
Walter J. Murphy, ATTORNEY

UNITED STATES PATENT OFFICE.

CONSTANT L. DEVOS, OF NEW YORK, N. Y.

WRENCH.

1,416,271.

Specification of Letters Patent. Patented May 16, 1922.

Application filed January 7, 1922. Serial No. 527,540.

To all whom it may concern:

Be it known that I, CONSTANT L. DEVOS, a citizen of the United States of America, residing at New York city, New York County, N. Y., have invented a new and useful Wrench, of which the following is a specification.

My invention relates to wrenches of the so-called socket type, the object being to provide a compact and reliable construction which may be used in places which are ordinarily very inaccessible and which can also be operated by means of a lever handle in the usual way or by means of gearing.

15 In the accompanying drawings:

Fig. 1 is a plan view of the wrench.

Fig. 2 is a section on the line 2—2 of Fig. 1.

Fig. 3 is a plan view of a detail.

20 Fig. 4 is a plan view of another detail.

5 represents an annular housing which has an integral tubular handle 6 projecting laterally from one side thereof. 7 is a socket member arranged to be rotatably supported 25 within the housing. 8 is a beveled flange at one end of the housing which constitutes an annular seat for the socket member 7. The adjacent side of the socket member 7 is flanged as at 9 and beveled to seat properly 30 on the flange 8. The opposite side of the flange 9 is provided with bevel teeth 12. 11 is a ring which is screw threaded into the opposite end of the housing to hold the socket member 7 in place, the said ring being 35 preferably provided with a left hand thread and with recesses to receive a spanner wrench whereby it may be easily applied and removed. 14 is a shaft which is arranged to be passed freely through the tubular handle 6. 13 are bevel teeth fixed on the inner end of said shaft arranged to mesh with the teeth 12 of the socket 7 whereby when the shaft 14 is turned the socket 7 will be turned within the housing 5. To hold 40 the shaft in position so that the thrust of the bevel gears will not force it away from the socket, I provide a collar 16 which screws on to the outer end of the handle 6 and has a shoulder which overstands a shoulder 15 45 on the shaft 14. 17 is a cap which may be provided at the outer end of the shaft 14, and 18 is a bar which slides loosely through a transverse passage in the outer end of the shaft by which bar sufficient leverage is 50 provided to permit the socket to be turned against substantial resistance. It will be ap-

parent that the angular position of the socket 7 may be varied relatively to the center line of the handle 6 so that the wrench may be slipped on to a nut located in a most 60 inaccessible place, and the nut may then be turned either by swinging the device bodily by means of the handle 6 or by holding the handle 6 still and turning the shaft 14. Sockets having passages of different sizes 65 and shapes may be provided to fit nuts of different sizes and shapes. To substitute one socket for another the user simply removes the ring 11, unscrews the collar 16 and retracts the shaft 14 sufficiently to cause the 70 gear 13 to become free of the gear 12 whereupon that particular socket may be removed and another one inserted. In the preferred form the shaft 14 is of a size to substantially fill the passage through the hollow handle 75 6 so that no separate bearing support is necessary. This also permits the gear 13 to be made of adequate size while still being of no greater diameter than the bore of the handle 6. 80

What I claim is:

1. A socket wrench comprising a ring-like housing having a tubular handle projecting laterally therefrom, a flange at one end of said housing forming a socket seat, a 85 socket having a flange one side of which is supported on said seat, the opposite side of said flange being toothed to form a gear, a removable keeper ring at the other end of said housing to hold said socket on said seat, a shaft having a gear at one end to coat with the gear of said socket, said shaft and gear being insertible and removable through said tubular handle, means for holding said shaft in position to hold said gears in mesh, 90 and means for turning said shaft within said handle to rotate said socket in said housing. 95

2. In a socket wrench, an annular housing having an integral tubular handle projecting laterally from one side thereof, a socket 100 mounted to rotate in said annular housing and means for removably holding the same therein, a beveled gear at the outer side of said socket, a shaft having a beveled gear at one end, said shaft and gear being insertible 105 and removable through said tubular housing, with means for holding said shaft in position to cause said beveled gears to mesh and to hold the same in mesh, said shaft being rotatable within said handle whereby said 110 socket may be rotated within said housing.

3. In a socket wrench, an annular housing

having an integral tubular handle projecting laterally from one side thereof, a socket mounted to rotate in said annular housing and means for removably holding the same 5 therein, a beveled gear at the outer side of said socket, a shaft having a beveled gear at one end, said shaft and gear being insertible and removable through said tubular housing, with means for holding said shaft in

position to cause said beveled gears to mesh 10 and to hold the same in mesh, said means comprising a sleeve removably secured to the outer end of the tubular handle with co-acting shoulders on said handle sleeve and shaft, said shaft being rotatable within said 15 handle whereby said socket may be rotated within said housing.

CONSTANT L. DEVOS.
